(57) **CLAIM**

We claim the ornamental design for a syringe adapter for medication, as shown and described.

DESCRIPTION

FIG. 1 is a perspective view of a syringe adapter, showing a first embodiment of our new design having a radial extension and a hexagonal element;

FIG. 2 is a front view thereof, the back view being identical thereto;

FIG. 3 is a top view thereof, the bottom view being identical thereto;

FIG. 4 is a left-side view thereof;

FIG. 5 is a right-side view thereof;

FIG. 6 is a perspective view of a syringe adapter, showing a second embodiment of our new design having a radial extension and a hexagonal element, and having a longer conical portion;

FIG. 7 is a front view thereof, the back view being identical thereto;

FIG. 8 is a top view thereof, the bottom view being identical thereto;

FIG. 9 is a left-side view thereof;

FIG. 10 is a right-side view thereof;

FIG. 11 is a perspective view of a syringe adapter, showing a third embodiment of our new design having a radial extension with a different diameter and a hexagonal element;

FIG. 12 is a front view thereof, the back view being identical thereto;

FIG. 13 is a top view thereof, the bottom view being identical thereto;

FIG. 14 is a left-side view thereof; and,

FIG. 15 is a right-side view thereof.

Features shown in the drawings using broken lines form no part of the claimed design.
